CUTTER HEAD

Ishmael H. Gearhart, Salem, Va.

Application September 10, 1946, Serial No. 695,987

5 Claims. (Cl. 12—92)

1

My present invention relates to improvements in the general class of boot and shoe making, and more specifically to a rotary cutter head of the axially adjustable type utilizing a quick detachable locking means between the cutter head and its power shaft, and novel means for shielding the cutter.

While the device of my invention is well adapted for various purposes, it is especially designed for use by shoemakers in repairing and manufacturing shoes. In trimming, dressing, and burnishing the edges of the soles of shoes, the edge of the shoe sole is manually held against the rotary tool, and the primary object of the invention is the provision of a rotary cutter that is provided with quick detachable means for interchangeable use of different types of cutters; and which is shielded for the protection of the operator, and to insure accurate and effective operations in dressing the shoe sole.

In its physical embodiment the invention includes a minimum number of compactly arranged parts that may be manufactured with facility and at low cost of production, and the parts may be assembled with convenience to provide a tool that is simple in construction and operation.

The invention consists essentially in certain novel combinations and arrangements of parts involving the specific quick-detachable means for locking the cutter head for rigid operation with the power shaft, and the particular resiliently supported and automatically adjusted shield for the cutter head, as will hereinafter be described and set forth in the appended claims.

In the accompanying drawings I have disclosed one complete example of a physical embodiment of my invention wherein the parts are combined and arranged in accord with one mode I have devised for the practical application of the principles of my invention, but it will be understood that changes and alterations may be made in these exemplifying drawings and mechanical structures, within the scope of my claims, without departing from the principles of the invention.

Figure 1 is a view in side elevation showing a rotary cutting tool in which my invention is embodied, and disclosing a portion of the supporting frame and the belt drive for the tool.

Figure 2 is an enlarged longitudinal sectional view through the cutting tool.

Figure 3 is a face view of the locking bushing of the cutter head.

Figure 4 is a detail view partly in section, as at line 4—4 of Fig. 3.

2

Figure 5 is a left end face view of the device in Fig. 4.

Figure 6 is a detail sectional view at line 6—6 of Fig. 3.

5 In the assembly view of Fig. 1 where the relation of parts is disclosed, the horizontally disposed power shaft 1 of a machine tool is journaled in bearings 2, 2, supported on the machine frame 3, and the pulley indicated at P, is driven by 10 the belt drive 4 for revolving or rotating the power shaft.

In carrying out my invention I preferably utilize an enlarged cylindrical shaft-head 5 that is fashioned with a socket 6 at one end, and the 15 socket is fitted over the end of the shaft and secured thereto by means of a pair of diametrically arranged screws 7, in order that the rigid head may revolve with the shaft.

To provide a resiliently adjustable safety shield 20 for the tool I employ a longitudinally slidable cylindrical sleeve 8 that is mounted on and revolves with the shaft-head 5, and the sleeve is provided at diametrically opposite points with longitudinally extending guide grooves or slots 25 9, through which the headed screws 7 pass for co-action with the slots.

The cylindrical sleeve is resiliently urged toward the free end of the shaft head, and for this purpose the rear portion of the sleeve is provided with an enlarged interior annular recess or enlarged bore 10 in which a helical spring 11 is mounted and interposed between the two screws 7, 7, and an annular shoulder 12 formed at the inner end of the enlarged bore or recess.

35 As best seen in Fig. 2, at its front end the shaft-head 5 is fashioned with an integral centrally arranged axial boss 13 of reduced diameter upon which the removable and interchangeable rotary cutting tool is mounted and locked by means of 40 a quick detachable fastening joint, and for this purpose the solid cylindrical boss is provided with a rigidly mounted transversely projecting radial pin 14.

The rotary cutter unit includes a bearing cup 45 or cylindrical bushing 15 closed at its outer end and mounted upon the bearing boss, and the inner bore of the bushing is provided with an interior spirally arranged groove 16 that terminates in a short longitudinally extending entrance groove 17, so that the bushing may be slipped over the boss, the pin 14 enters the slot 17, and a one-eighth turn of the bushing, through the co-action of the pin and groove 16, rigidly locks the bushing on the boss. The bushing is partially 55 turned in the direction opposite to that of the

3

rotation of the shaft to lock the bushing on the boss; and a reverse turn or partial turn of the bushing readily releases the bushing so that it may quickly be detached from the boss.

One of the interchangeable rotary cutters, as 18, is shown mounted with its hub 19 on the exterior of the bushing and located with the open front end of the tubular slide or sleeve 8, and the flush ends of the bushing and hub abutting the flat end or face of the shaft head.

The inner annular edge of the cutter 18 is surrounded by and enclosed within an exterior annular flange 20 integral with the outer end of the slide sleeve, which forms a sheath or shield for the cutter, and the spring arrangement between the sleeve and the shaft head provides resilient means for automatically adjusting the sleeve with relation to the cutter.

The cutter 18 is rigidly mounted upon its bearing bushing to revolve with the bushing, when the latter is locked on the boss. The cutter 13 being rigidly mounted on the bushing 15 by means of a flat circular disk or plate 21 having a tapered edge on its outer face, and a fastening screw or bolt 22 is passed through a central hole in the disk or plate and threaded in a central opening in the closed end of the bushing. The plate or disk forms an exterior shield for the cutter, and the plate with its screw provides a rigid fastening means for mounting the cutter on its bushing.

The cutter head including the bushing may readily be unlocked from the supporting boss and detached when desired, and the cutter may with equal facility be removed from the bushing by backing off the screw and the retaining plate or disk that forms a shield for the cutter.

Having thus fully described my invention, what I claim as new and desire to secure by Letters Patent is:

1. In a rotary cutting tool, the combination with a power shaft, having an enlarged cylindrical shaft-head on the forward end of said shaft, an axial boss on the forward end of said head centrally thereof, and a radial locking pin on the boss, of a locking bushing mounted for partial rotation on the boss, said bushing having an inner spiral groove co-acting with said radial pin, a rotary cutter mounted on the bushing, an outer disk-shaped shield for the cutter, a fastening screw passed through an opening in the shield and threaded in the bushing, a spring pressed sleeve on said head engaging said cutter to urge said cutter outwardly of said head when the pin in said boss is disengaged from the groove in said bushing, and means carried by said head to slidably retain said sleeve on said head.

2. In a rotary cutting tool, the combination with a power shaft, a shaft-head on said shaft having a reduced axial boss, a bushing mounted on said boss, a rotary cutter head on said bushing, and quick-detachable means for locking the bushing on the boss, of a longitudinally slidable spring pressed sleeve mounted on the shaft-head to rotate therewith, and an annular flange at the

4

outer end of the sleeve forming a shield for the rotary cutter and engageable therewith, said sleeve tending to force said cutter outwardly of said head when said cutter is released from said boss.

3. In a rotary cutting tool, the combination with a power shaft and a head on said shaft having a reduced axial boss, a bushing mounted on said boss, a rotary cutter head on said bushing, and quick-detachable means for locking the cutter head on the bushing, of a spring-pressed slotted sleeve mounted on the shaft-head, guide members carried by the shaft-head and engaged in the slotted sleeve, and an annular flange at the outer end of the sleeve forming a shield for the rotary cutter head and engaging said head, said sleeve tending to force said cutter outwardly of said head when said cutter is released from said boss.

4. In a rotary cutting tool, the combination with a power shaft and a head on the shaft having a reduced axial boss, a radial locking pin on the boss, a locking bushing having an inner spiral groove for co-action with said pin and mounted on the boss, and a rotary cutter head mounted on the bushing, of a longitudinally spring pressed sleeve mounted on the shaft head to rotate therewith, and an annular flange at the outer end of the sleeve forming a shield for the cutter head and engaging the head, said sleeve tending to force said cutter outwardly of said head when said pin is disengaged from said groove.

5. In a rotary cutting tool, the combination with a power shaft and a head on the shaft having a reduced axial boss, a radial locking pin on the boss, a locking bushing having an inner spiral groove co-acting with the pin mounted on the bushing, a rotary cutter head mounted on the bushing, an outer disk-shaped shield for the cutter head, and a screw fastening said shield to the bushing, of a spring pressed slotted sleeve mounted on the shaft head, guide member members carried by the shaft head and projected through the slotted sleeve, and an annular flange at the outer end of the sleeve forming an overhanging shield for the rotary cutter head and engaging the head and tending to force said cutter outwardly of said head when said pin is disengaged from said groove.
